UNITED STATES PATENT OFFICE.

HANS METTLER, OF AARAU, SWITZERLAND.

DRAWING INSTRUMENT.

No. 852,132.

Specification of Letters Patent.

Patented April 30, 1907.

Application filed June 28, 1906. Serial No. 323,948.

To all whom it may concern:

Be it known that I, HANS METTLER, a citizen of Switzerland, residing in Aarau, in the canton of Aargau, Republic of Switzerland, (whose post-office address is 1407 Entfelderstrasse, Aarau,) have invented certain new and useful Improvements in Drawing Instruments; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the drawing instrument herewith described with spring jaws and means for adjusting the same, each jaw has a wedge-shaped part and there is a piece which by action upon the wedge-shaped parts imposes to the jaws a movement opposite to that due to the spring action of the jaws.

The annexed drawing shows a fountain ruling pen as one form of construction of the new instrument.

Figure 1 is a longitudinal vertical section, Fig. 2 is partly a longitudinal horizontal section and partly a plan. Fig. 3 is an elevation showing the instrument in open position. Fig. 4 and 5 are cross sections on lines A—B and C—D in Fig. 1 and 2.

A is the coupling sleeve having an outer screw thread by means of which the sleeve can be screwed into the ink holding pen holder. The sleeve A has also an inner screw thread into which is screwed a tube B which surrounds the ink feeding tube C.

D is the ruling pen carried by the tube B and held thereupon by frictional contact. The jaws D' of the pen have the tendency to open themselves by elasticity. Each of the jaws has a wedge shaped part d and two lateral notches d¹ giving the jaw the required elasticity. The rear cylindrical part of the pen has a screw thread d² on its periphery upon which thread the rear end of the threaded sleeve E is screwed. The front part of the sleeve E is fitted on its interior to

the wedge shaped parts d of the jaws D', the remaining portion of the bore of the sleeve 50 being cylindrical.

In screwing up the sleeve, its front part presses upon the wedge shaped parts of the jaws, closing them opposite to the spring action of the jaws. In reversing the movement, the jaws are allowed to open, so as the same may be easily cleaned (Fig. 3).

The manipulation of the ruling pen is very simple, the adjustment of the jaws very accurate. No drilling and threading of the jaws or any adjusting bolt is necessary. The jaws of the new drawing instrument may also be formed in such a way, that those surfaces of the wedge - shape parts upon which an opening or closing action has to take place, 65 are on the inside of the jaws. In this case, the piece acting upon the said surfaces should be placed between them and the spring action of the jaws should tend to close the pen. In order to easily adjust the jaws to the desired thickness of lines, the cylindrical part of the ruling pen is provided with a scale D³ (Fig. 2) over which the sleeve E can move. 70

What I claim is:—

In a drawing instrument of the character 75 described, the combination with the tube B, of a ruling pen D mounted on said tube, the rear portion of said pen being provided with a scale and with an exterior screw-thread d² and the forward end of said pen being provided with spring jaws, each of which latter has a wedge shaped portion d intermediate the screw-thread and the forward end of said jaws, and a sleeve E interiorly threaded and screwing upon the screw-thread of the pen D 80 and playing over the scale thereon, the forward end of the sleeve E being adapted to bear upon the tapered portion of the jaws for the purpose set forth.

In testimony whereof, I have signed my 90 name to this specification in the presence of two subscribing witnesses:

HANS METTLER.

Witnesses:

HERMANN HUBER,
A. LIEBERKNECHT.
